C. F. GERLINGER.

BUNK AND LOCKING BLOCK FOR LOGGING CARS.

APPLICATION FILED JUNE 18, 1913.

1,071,997.

Patented Sept. 2, 1913.

UNITED STATES PATENT OFFICE.

CARL F. GERLINGER, OF DALLAS, OREGON.

BUNK AND LOCKING-BLOCK FOR LOGGING-CARS.

1,071,997.

Specification of Letters Patent.

Patented Sept. 2, 1913.

Application filed June 18, 1913. Serial No. 774,410.

To all whom it may concern:

Be it known that I, CARL F. GERLINGER, a citizen of the United States, residing in Dallas, in the county of Polk and State of Oregon, have invented certain new and useful Improvements in Bunks and Locking-Blocks for Logging-Cars, of which the following is a specification.

This invention relates to that part of a logging car known as the bunk which supports the logs and which is equipped with chocks for holding the logs in place on the bunks. It is customary to so mount the chocks in the bunks that they may be lowered to release the logs when the car is dumped, and various arrangements have been suggested for raising and lowering the chocks for this purpose.

According to my invention I provide a log bunk with improved chocks and novel chock-operating devices of simple and durable construction which may be operated from the side of a car opposite that from which the logs are delivered and which, when in proper position, hold the logs securely but when lowered are entirely withdrawn from the logs, thus permitting them to be readily discharged.

In the accompanying drawings:—Figure 30 1 is a perspective view, showing the outline of a logging car with my improvements applied. The remaining figures are on an enlarged scale. Fig. 2 is a detail view, partly in elevation and partly in section, and with 35 parts broken away, showing how one of the chock blocks is mounted and operated in a bunk. Fig. 3 is a perspective view of one of the chock blocks. Fig. 4 is a perspective view of one of the links employed in connection with each chock block. Fig. 5 is a detail view, in section, on the line 5—5 of Fig. 2.

The outline only of a logging car A is shown, but my improvements may be applied to cars of various construction. Each bunk B consists of two ordinary railroad rails b placed side by side and secured to the platform of the car. At each end of each pair of rails I mount a chock block C, which 45 is arranged between the rails of the pair and is pivotally connected at one end with them. At its opposite end each block is pivotally connected with one end of a link D, the opposite end of which is provided with laterally projecting arms d, for a purpose herein- 50 after described. Each block C is formed

with laterally projecting arms e and an opening extends through the arms and block to receive a bolt E which also extends through the rails and thus pivotally connects the block with the rails. Each block is formed with a recess e' to receive one end of a link D and a bolt or pin F pivotally connects the link with the block. 60

The arms d of the link D enter recesses d' in the ends of the rails, as clearly shown in Fig. 2. When a block is set for holding the logs the parts are in the position illustrated, with the arms d in the recesses d', but when the arms d are withdrawn from the recesses 70 d' the block and link drop into the position shown by dotted lines in Fig. 2.

It will be understood that there is a chock block at each end of each bunk and each of the blocks is of the construction shown, and 75 is pivotally connected with a link. The outer end d² of one of the arms d of each link engages the hooked end g of a rod G which extends along the outside of one of the rails b and may be guided by wire 80 guides H. The end of the rod G, opposite to its hooked end, has attached to it a downwardly extending arm I which is provided with a laterally extending arm i that extends through a bar J pivotally connected 85 by a bolt K to the car frame. A cotter-pin L prevents the separation of the bar J from the arm I. When the parts are in the position shown in the drawings, with the hook g engaging the arm d² and with the arm I 90 engaged with the bar J the chock is held in the position shown by full lines in Fig. 2.

When it is desired to unload the car, the chock may be lowered by withdrawing the cotter-pin, swinging the bar J clear of the 95 arm i and then the rod G may be moved outwardly, the arms d released from the recesses d', and the link D and block C will drop to the position shown by dotted lines. All of the chocks are operated in a similar 100 way, and it will be observed that the blocks can only be released from that side of the car opposite to the side where the chocks to be lowered are located. In order to restore the chocks to their operative position, it is 105 only necessary to raise the blocks with the links and place the arms d in the recesses d', engage the hooks g with the arms and engage the arms I with the rods L in the manner before described. 110

It will be observed that I employ ordinary railway rails and that the parts of the

2
mechanism are few, strong, durable and easily operated.

I claim as my invention:

1. The combination with a logging car of a bunk consisting of a pair of rails provided with notches at one end, a chock block mounted between the rails and pivotally connected therewith, a link pivotally connected with the outer end of the chock block and provided with devices engaging the notches in the rails, a rod having a hooked end detachably connected with the link and extending to the opposite side of the car; and means for holding said rod against endwise movement.
2. The combination with a logging car of a bunk attached thereto, a chock block pivotally connected at one end with the bunk, a link pivotally connected with the opposite end of the block and provided with laterally projecting arms, a hooked rod engaging one of said arms and extending parallel with the bunk to the opposite side of the car;

a downwardly extending arm attached to said rod, and a bar pivotally connected with the car and engaging said arm.

3. The combination with a logging car of a bunk, comprising two railway rails placed side by side and attached to the car, a chock block mounted between the rails and pivotally connected therewith, a link pivotally connected with the chock block and provided with laterally projecting arms engaging recesses in the rails, a rod having a hooked end engaging one of said arms on the link and extending parallel with the rails to the opposite side of the car; a downwardly extending arm attached to said rod; and a bar connected with the car and engaging said arm.

In testimony whereof, I have hereunto subscribed my name.

CARL F. GERLINGER.
